UNITED STATES PATENT OFFICE.

GLENN STANLEY BOUTELL, OF HOLLAND, MICHIGAN.

PISTON CONSTRUCTION.

Application filed April 23, 1925. Serial No. 26,892.

This invention relates to improvements in piston constructions.

The primary object of this invention is the provision of an improved type of self-expanding piston, which embodies a light, durable, and flexible construction.

A further object of this invention is the provision of a piston embodying a novel principle of self expansion, which will do away with the use of piston rings and like expedients, and which is so formed as to provide an absolute seal in its operation in an internal combustion engine cylinder, to prevent loss of compression, and to accurately conform in snug fitting and sealing relation to the cylinder.

A further object of this invention is the provision of a novel type of adjustable means for maintaining the piston pin in a firm seating relation with respect to a connecting rod and bearings in the piston body, to prevent slap and vibration incident to operation.

Other objects and advantages of this invention will be apparent during the course of the following detailed description.

In the accompanying drawings, forming a part of this specification, and wherein similar reference characters designate corresponding parts throughout the several views.

Figure 1 is a side elevation of the improved type of piston construction adapted for use in internal combustion engines.

Figure 2 is a cross sectional view taken substantially on the line 2—2 of Figure 1.

Figures 3 and 4 are cross sectional views taken substantially on their respective lines in Figure 2 of the drawings.

Figure 5 is a sectional view taken substantially on the line 5—5 of Figure 3, and showing more particularly the construction of the head of the piston.

Figure 6 is a plan view of a piston embodying the improved principle of this invention; this piston being of the type generally used in steam engines, and other places where a compact piston is desired which is self-expanding.

Figure 7 is a sectional view taken substantially on the line 7—7 of Figure 6.

Figure 8 is a sectional view taken substantially on the line 8—8 of Figure 7.

Figure 9 is a side elevation of the improved piston illustrated in Figure 6.

In the drawings, wherein for the purpose

of illustration are shown preferred and modified forms of the improved piston construction, the letter A may generally designate the type of piston adapted for internal combustion engine use, and B the type of piston adapted for steam engine use.

Referring to the piston construction A, the same preferably comprises a body or skirt portion 10; crescent shaped gap filling member 11 cooperatively associated with the body 10; head member 12; means 13 for maintaining the head 12 in an assembled relation on the piston body; and an expanding member 15.

The body 10 of the piston construction A is preferably cast in hollow cylindrical form, and a plurality of the same are cast integral and subsequently severed. This body 10 comprises a lower thin walled portion 20 and an upper thicker walled portion 22. The upper portion 22 is provided with a substantially crescent shaped eccentric seat 24, formed by throwing the body 10 off center and cutting into the portion 22 from the outer periphery of the said portion, until such eccentric seat 24 is formed. The eccentric seat 24 extends for substantially one-half the circumference of the portion 22, and between the ends of this seat 24, the portion 22 is cut entirely through, to provide the gap 25. Thus, the ends 27 of the portion 22 are tapered to a sharp edge at the gap 25, as is illustrated in Figure 2 of the drawings.

The seat 24 extends to the extreme upper edge 30 of the portion 22, and the same provides a shoulder 31 at the juncture of the portions 20 and 22 of the body 10, as is illustrated in Figure 4 of the drawings, and upon which shoulder 31 the crescent shaped member 11 is adapted to rest, and form the complement for rendering the portion 22 circular at its outer periphery, for snug fitting in the engine cylinder.

The portion 20 is preferably diagonally slotted at 35 from the shoulder 31 to the lower edge 36 thereof, as is illustrated in Figure 1 of the drawings, and preferably immediately below the gap 25. Thus, by the provision of the gap 25 and the slot 35 the piston body 10 is split from end to end, so that the same may expand incident to forces operating thereon. Tubular piston or wrist pin bearing extensions 38 and 39 are formed integral with the portion 20, preferably just below the eccentric seat 24, extending into the compartment 40 within said

portion 20, and providing aligning openings 41 for receiving the wrist pin 42 in diametrical extension across the piston body 10. It is preferred that the passageways 41 be bored and reamed over sized to compensate for piston body extension or contraction. A circular seat 45 is milled inwardly of the portion 22 from the upper edge 30 thereof, eccentric to the axis of the piston, within which the expansion spring 15 is adapted to be placed. The stock of the body 10 is preferably left at the inside of the body 10 adjacent the juncture of the portions 20 and 21, to provide an inwardly extending annular flange 49 on which the expansion ring 15 rests. In its resting position on this flange 49 the top edge 50 of the expansion ring 15 is preferably just slightly below the top edge 30 of the piston body 10, so that the top or head 12 may seat on the edge 30 in lieu of on the expansion ring 15. This gives an effective seal of the head and body of the piston and does not obstruct the expansive action of the ring 15.

25 The expansion ring 15 is preferably split at 55, and diametrically opposed to the split 55 the same is preferably provided with a recess adapted to receive a centering pin 56, said centering pin 56 being projected into a suitable recess formed at the inside of the segmental or crescent shaped piece 11, to hold the latter in centering relation to the body of the piston, against liability of its displacement with respect to other details 30 of the body of the piston.

40 The crescent shaped or segmental shaped member 11 is relatively wide, and in length extends for an arc of approximately 180°. From its central portion adjacent the pin 56 the same tapers to sharp edges at its outer ends, to give the crescent shape to the same. In its seat 24 in the piston body the outer surface 60 thereof is in concentric relation with the outer surface 61 of the body portion 22 of the piston A, as is illustrated in Figure 2 of the drawings. When assembled in this relation oil grooves 62 are preferably cut inwardly of the peripheries 60 and 61 through the portions 11 and 22 of the piston, and lowermost oil grooves 63 are similarly provided inwardly of the periphery of the portion 20 of the body 10.

45 The head 12 is preferably of disc-shaped formation, and adapted at its outer margins to overlap the edge 30 of the body 10, preferably with a ground joint.

50 The means 13 for retaining the head 12 in position on the top of the piston body 10 preferably comprises a substantially U-shaped yoke 65, including the leg portions 66, which at their lower ends are apertured at 67 for receiving the piston pin 42 therethrough. This yoke 65 furthermore comprises the connecting portion 68 which holds the legs 66 in a parallel relation, and this

55 connecting portion 68 is provided with a vertical opening 69 therethrough adapted to slidably receive the shank of a bolt 70. The head of the bolt 70 extends below the connecting portion 68 and between the legs 66, above the wrist pin 42, and is adapted to support a compression spring 71. The bolt 70 at its opposite end is screw threaded, for screw threaded extension thru a screw threaded opening 73 provided centrally of 75 the piston head 12. In its upper surface the piston head 12 is provided with a countersunk recess 74 for receiving a lock nut 75 therein. This lock nut is adapted for receiving the upper screw threaded end of the 80 bolt 70 to maintain the same in a definitely locked relation with the head 12, and a cotter pin 76 may be used for locking the nut to the shank of the bolt 70, as is illustrated in Figure 3 of the drawings. The upper end 85 of the bolt 70 is provided with a kerf, as is illustrated in Figure 4 of the drawings, adapted to receive the end of a screwdriver, and the lock nut 75 may have openings therein for a spanner wrench. In this manner, 90 by removal of the cotter pin the compression of the spring 71 may be adjusted.

95 Referring to the construction of the type of piston B, the same includes a body structure 80, adapted for support in any approved manner upon the piston rod 81. The body structure 80 is adapted to receive an expandable arrangement consisting of complementary portions 82 and 83, and means 84 to effect expansion.

100 The body 80 preferably comprises the sections 85 and 86, which are similarly formed, each including hub portions 87 provided with passageways 88 therethrough; web portions 89; and rim portions 90 having outwardly extending flanges 91 at the outer edges thereof. The sections 85 and 86 are adapted to be bolted, as at 92, through the web portions 89, and this places the openings 88 in aligning relation for detachably receiving the attaching ends of the piston rod 81. The rim portions 90 are right angled with respect to the portions 89, and the flanges 91 are thus spaced to provide the annular recess 92 adapted to receive the expansion arrangement comprising the sections 82 and 83 and the expansion rim 84. Annular projections 95 may be formed contiguous with the webs 89, extending into the recess 92 between the flanges 91, and against which expansion ring 84 bears. The expansion ring 84 is of the split type, being split as at 100, and it is placed in the groove 92 between the flanges 91. This groove 92 is very wide, extending practically the entire width of the body 80 of the piston, with the exception of the flanges 91.

105 110 115 120 125 130 The complementary sections 82 and 83 are of the expandable form and design of the portions 11 and 22 of the form of invention

A. The section 82 is provided with the outer cylinder engaging circumference 101, and at one side thereof the same is eccentrically cut with respect to the center of the 5 circumference 101 to provide the eccentric seat 102, which converges into intersecting relation with the inside periphery 103, to provide a gap 104. The section 82 is thus split, and from the gap 104 the ends 105 thereof taper in increasing thickness. The section 83 may be referred to as a crescent shaped or segmental section or member, and it is formed of an arc substantially 180°, or 10 slightly less, tapering in thickness from intermediate its ends to sharp edges at its outer end. The same is complementary 15 with the section 82 and adapted to seat in the eccentric seat 102, so that the outer surface 110 thereof is concentric with the cylinder engaging surface 101 of the section 82. In this position of parts the crescent shaped member 83 extends across the gap 104. The pin 115 may be carried by the body 80, extending radially therefrom into the groove 20 92, and through suitable openings 116 and 117 respectively provided in the split ring 84 and crescent shaped member 83; said pin 115 extending thru the gap 104 to hold the segmental or crescent shaped member 83 in proper centered relation with respect to its 25 complementary section 82.

The sections 82 and 83 when assembled in the body of the piston are forced into a normally expanded relation by the expansion ring 84, which is eccentrically disposed in the section 82, with its axis eccentric to the axis of the piston B, as is the case with the expansion ring structure of the piston A. This enables the piston construction to be 30 made of less material and lightens the same and provides an efficient and durable construction. The sections 82 and 83 when assembled are provided with circumferential oil grooves 120.

45 From the foregoing description of this invention it will be apparent that a novel type of piston construction has been provided, which is self expanding, and of particular merit in that no open slots or recesses are exposed at the firing side of the piston to occasion loss of compression. The piston construction in addition to these advantages is light in weight, and very flexible, and because of the crescent shaped piece the novel expansion construction is enabled to be provided, with the expansible portion of the piston having a gap which is effectively sealed. The construction dispenses with the use of inefficient piston rings.

50 In addition to the foregoing advantages, other advantages will be apparent to those skilled in this art, and it is also to be noted that the upper connecting rod bearings of an engine fitted with the style of piston A 55 will never knock or become noisy, since there

is a take-up of wear which is automatic in action.

Various changes in the shape, size, and arrangement of parts may be made to the forms of invention herein shown and described, without departing from the spirit of the same or the scope of the claims.

I claim:

1. In a piston a split body portion having an eccentric seat at the outer surface thereof across said split therein, and a substantially crescent shaped complementary portion adapted for cooperation in said eccentric seat.

2. As an article of manufacture an expansible piston construction comprising a pair of complementary sections including a major section having an eccentrically formed exterior seat and being split to provide a gap on said seat, and a minor segmental shaped section adapted to be placed on said eccentric seat so that the outer surfaces of said sections form a true circle.

3. In a piston construction the combination of a pair of complementary sections, one of said sections having the ends thereof tapered in diminishing relation and at the free ends thereof providing a gap, said section exteriorly thereof having a seat formed eccentric to the axis of the piston construction, the other of said sections comprising a substantially crescent shaped body adapted to seat on the eccentric seat of the first mentioned section in a complementary relation so that the outer circumference thereof is concentrically arranged with the exposed outer surface of the first mentioned section.

4. In a piston construction the combination of a pair of complementary sections, one of said sections having the ends thereof tapered in diminishing relation and at the free ends thereof providing a gap, said section exteriorly thereof having a seat formed eccentric to the axis of the piston construction, the other of said sections comprising a substantially crescent shaped body adapted to seat on the eccentric seat of the first mentioned section in a complementary relation so that the outer circumference thereof is concentrically arranged with the exposed outer surface of the first mentioned section, and expansion means acting within the first mentioned section normally tending to expand the first mentioned section to open the gap thereof.

5. In a piston construction the combination of a pair of complementary segments eccentrically seated with respect to each other to provide a substantially ring shaped structure, and an expansion ring seated within said ring shaped structure tending to expand the same.

6. In a piston construction of the class described the combination of a pair of substantially segmental complementary sections

providing a ring shaped structure the outer surfaces of which form a true and unbroken circle, one of said sections being a major section whose ends taper to provide a gap, 5 the major section having the ends thereof providing an eccentric seat at the outer surface thereof, and the other section comprising a substantially crescent shaped minor section adapted to be placed on said eccentric seat across said gap of the major section 10 in sealing relation therewith, and expansion means acting on said sections tending to expand the same.

7. In a piston construction of the class 15 described the combination of a pair of substantially segmental complementary sections providing a ring shaped structure the outer surfaces of which form a true and unbroken circle, one of said sections being a major 20 section whose ends taper to provide a gap, the major section having the ends thereof providing an eccentric seat at the outer surface thereof, and the other section comprising a substantially crescent shaped minor 25 section adapted to be placed on said eccentric seat across said gap of the major section in sealing relation therewith, a split expansion ring seated at the inner periphery of 30 said complementary sections tending to expand the same, and a pin extending from said split ring through the gap of the major section into a seat provided in the crescent shaped minor section.

8. A piston comprising a substantially 35 cylindrical shaped body portion split from end to end, said body portion inwardly of the outer surface thereof providing a seat eccentrically disposed with respect to the axis of said body and extending across the split of said body, and a substantially crescent shaped complementary gap sealing section seated on said eccentric seat.

9. A piston comprising a substantially cylindrical shaped body portion split from end 40 to end, said body portion inwardly of the outer surface thereof providing a seat eccentrically disposed with respect to the axis of said body and extending across the split of said body, a substantially crescent shaped complementary gap sealing section seated on said eccentric seat, and means within the body of said piston for expanding the same at the gap across which said crescent shaped section seats.

55 10. A piston construction comprising a body of substantially cylindrical formation having a seat eccentrically formed inwardly at the outer surface thereof of a width less than the height of said piston, said piston 60 being split from end to end extending through said eccentric seat, and a crescent shaped segment adapted to be placed on the eccentric seat in complementary relation with the piston body to seal the split of said 65 piston body across said seat and so that the

outer surface of the crescent shaped segment is in concentric relation with the axis of said body.

11. A piston construction comprising a body of substantially cylindrical formation 70 having a seat eccentrically formed inwardly at the outer surface thereof of a width less than the height of said piston, said piston being split from end to end extending through said eccentric seat, a crescent shaped 75 segment adapted to be placed on the eccentric seat in complementary relation with the piston body to seal the split of said piston body across said seat and so that the outer surface of the crescent shaped segment is in concentric relation with the axis of said body, and a split expansion ring within said piston body acting thereon adjacent said eccentric seat and extending across the gap of the body adjacent said eccentric seat. 85

12. A piston construction comprising a body of substantially cylindrical formation having a seat eccentrically formed inwardly at the outer surface thereof of a width less than the height of said piston, said piston being split from end to end extending through said eccentric seat, a crescent shaped segment adapted to be placed on the eccentric seat in complementary relation with the piston body to seal the split of said piston body across said seat and so that the outer surface of the crescent shaped segment is in concentric relation with the axis of said body, a split expansion ring within said piston body acting thereon adjacent said eccentric seat and extending across the gap of the body adjacent said eccentric seat, and a pin carried by said split expansion ring extending through the gap of the piston body into the crescent shaped segment. 95 100

13. In a piston construction the combination of a body including a lower portion whose outer surface is concentrically arranged with the piston body and including an upper portion having an eccentric seat, 110 said body being split through the lower portion and through the eccentric seat of the upper portion, and a substantially crescent shaped segment for said eccentric seat adapted to fill the gap formed by the split across said eccentric seat.

14. In a piston construction the combination of a body including a lower portion whose outer surface is concentrically arranged with the piston body and including an upper portion having an eccentric seat, 120 said body being split from end to end thru the eccentric seat of the upper portion, a substantially crescent shaped segment for said eccentric seat adapted to fill the gap 125 formed by the split across said eccentric seat, and means acting within the piston body tending to expand the same at said split at the eccentric seat.

15. In a piston construction the combina- 130

tion of a hollow cylindrical shaped skirt comprising a lower split portion of one piece formation and an upper split portion having an eccentric seat inwardly of the outer surface thereof across the split therein extending from said lower portion upwardly, and a substantially crescent shaped complementary section for the upper portion adapted to rest in said eccentric seat across the split of said upper portion.

16. In a piston construction the combination of a hollow cylindrical shaped skirt comprising a lower split portion of one piece formation and an upper split portion having an eccentric seat inwardly of the outer surface thereof across the split therein extending from said lower portion upwardly, a substantially crescent shaped complementary section for the upper portion adapted to rest in said eccentric seat across the split of said upper portion, and a split expansion ring acting in the skirt of said piston at said upper portion.

17. In a piston construction the combination of a hollow cylindrical shaped skirt comprising a lower split portion of one piece formation and an upper split portion having an eccentric seat inwardly of the outer surface thereof across the split therein extending from said lower portion upwardly, a substantially crescent shaped complementary section for the upper portion adapted to rest in said eccentric seat across the split of

said upper portion, a split expansion ring acting in the skirt of said piston at said upper portion, and a detachable head for said piston.

18. In a piston construction the combination of a substantially cylindrical shaped hollow skirt open at opposite ends thereof, a head for the open upper end of said skirt, a wrist pin construction supported by said skirt, a yoke carried by said pin extending upwardly to said head, a bolt adjustably carried by said head extending into said yoke, and a spring under compression between said bolt and yoke for maintaining the head in resilient engagement with said skirt.

19. In a piston construction the combination of a substantially cylindrical shaped hollow skirt open at opposite ends thereof, a head for the open upper end of said skirt, a wrist pin construction supported by said skirt, a yoke carried by said pin extending upwardly from said head, a bolt adjustably carried by said head extending into said yoke, a spring under compression between said bolt and yoke for maintaining the head in resilient engagement with said skirt, said bolt at its upper end extending through the head of said skirt, and being exteriorly screw threaded, and a lock nut for engagement with said exteriorly screw threaded bolt at the outer surface of said head.

GLENN STANLEY BOUTELL.
